METHOD OF AND APPARATUS FOR
FEEDING SHEETS**Leonard Baker, Hillsdale, N. J., assignor to Dexter
Folder Company, New York, N. Y., a corpora-
tion of New York**

Application August 24, 1937, Serial No. 160,581

24 Claims. (CL. 271—31)

This invention relates to sheet feeders and, while capable of general use, is more particularly adapted for feeding sheets of paper, tin, cardboard, or other materials one after another from the top of a pile thereof to various types of machines that are fed with and act upon such sheets.

One object of the present invention is to provide a method for continuously feeding sheets from the top of a pile through addition of sheets vertically to the bottom thereof during the feeding operation.

Another object of the present invention is to provide an improved sheet feeder that can be reloaded with sheets whenever necessary without having to stop the feeder and without interrupting the feeding of sheets therefrom to the machine being fed thereby.

Another object of the present invention is to provide a sheet feeder of the pile type that enables a pile of sheets thereon to be replenished from below while the sheets are being fed one after another from the top of the pile.

Another object of the present invention is to provide a sheet feeder of the pile type which, through the provision of a temporary support for the remainder of a pile of sheets, and mechanism capable of elevating a new pile to replenish the preceding pile, enables sheets to be fed continuously in succession from the top of the pile without having to stop the feeder to reload it.

Another object of the present invention is to provide a sheet feeder of the pile type which, through the provision of sheet separating and forwarding devices having working strokes of considerable length, a temporary support for the remainder of a pile of sheets, and pile elevating mechanism capable of raising a new pile to replenish the preceding pile, enables sheets to be fed continuously one after another from the top of the pile without having to stop the feeder for reloading or any other purposes.

Another object of the present invention is to provide a sheet feeder of the pile type wherein pile supports are movable into and out of the feeder as desired to maintain a continuous supply of sheets therein and sheet separating and forwarding devices are enabled to feed sheets successively from the top of said supply while it is being replenished at the bottom thereof by sheets elevated thereto.

These and other objects of the present invention will appear as the following description thereof proceeds and in order to more clearly understand said invention reference may be had to

the accompanying drawings illustrating on embodiment thereof.

In said drawings:

Fig. 1 is a side elevation of a sheet feeder constructed and operated in accordance with the present invention;

Figs. 2 and 3 are rear and front elevations, respectively, of the sheet feeder shown in Fig. 1;

Fig. 4 is a fragmentary, detail perspective view of sheet supporting means embodying the present invention;

Fig. 5 is an enlarged vertical longitudinal sectional view of part of pile elevator driving mechanism and control means therefor shown in Fig. 1;

Fig. 6 is a fragmentary rear elevation, partly in section, of the control means shown in Fig. 5 looking from the right thereof; and

Fig. 7 is a fragmentary vertical longitudinal sectional view of the feeder shown in Figs. 1 to 3.

Referring to the drawings, wherein like reference characters indicate like parts throughout the several views, the various movable parts of the feeder as well as certain stationary parts thereof may be mounted on a frame of any suitable construction and the movable parts may be actuated or driven by any suitable means. As herein shown, said frame and driving means are preferably constructed as follows.

The feeder frame is comprised by front uprights 5 and rear uprights 6 connected together by side members 7 and 8 (Figs. 1 to 3 and 7). The uprights 5 and 6 are bolted or otherwise suitably secured to the feeder foundation, the front uprights 5 being connected together by cross members 9 bolted or otherwise suitably secured thereto, and the rear uprights 6 being connected together at the tops thereof by a stay shaft 10 suitably secured thereto. The cross members 9 have bolted or otherwise suitably secured thereto a metal apron or plate 11 against which the front edges of the metal or other sheets 12 bear during elevation of the same and prior to feeding thereof one after another by mechanism to be hereinafter described.

Referring now more particularly to Fig. 3, the main drive for the feeder may be comprised by a chain 13 driven from any suitable source of power (not shown) and passing around a sprocket 14 that is fixed on a short shaft 15 journalled in suitable bearings in the adjacent front upright 5. Fixed on the short shaft 15 is a spur pinion 16 that meshes with a spur pinion 17 which, in turn, is fixed on a cam shaft 18. This cam shaft 18

18 is journalled in suitable bearings in the front uprights 5 and said cam shaft is utilized to operate various parts of the feeder hereinafter described.

5 The short shaft 15 has fixed thereon a crank disc 19 having pivotally connected therewith one end of a link 20 the opposite end of which is pivotally connected with a pawl carrier 21 that is loosely mounted on a shaft 22 (Fig. 3). This 10 shaft 22 extends transversely of the feeder and is journalled in suitable bearings in brackets 23 (Figs. 1 and 3) that are bolted or otherwise suitably secured to the front uprights 5 at the upper ends thereof. The shaft 22 may be rotated 15 intermittently in the proper direction to impart step by step upward movement to a pile of sheets A on a pile elevator hereinafter described, and this intermittent rotation of shaft 22 is preferably effected by pawl and ratchet mechanism of 20 the general type disclosed in the application Serial No. 33,002 of Leonard Baker, filed July 25, 1933.

This pawl and ratchet mechanism includes the pawl carrier 21 (Fig. 3) which has a pawl 24 pivoted thereon and adapted, under certain conditions, to engage a ratchet 25 fixed on the shaft 22. It will thus appear that thru oscillation of the pawl carrier 21 by the described driving connections therefor with chain 13, and through 30 engagement of the oscillating pawl 24 with the ratchet 25, the shaft 22 will be intermittently rotated as pointed out above. Under these conditions right and left hand worms 26 (Fig. 2) fixed on shaft 22 will likewise be rotated. These 35 worms 26 mesh with right and left worm gears 27 that are fixed on shafts 28 (Figs. 1 to 3 and 7) journalled in suitable bearings provided by the brackets 23 on the front uprights 5 and by brackets 29 on the rear uprights 6. Fixed on shafts 28 40 are sprockets 30 around which pass endless chains 31 which also pass around sprockets 32 that are fixed on shafts 33 journalled in suitable bearings in brackets 34 adjustably secured at 35 (Fig. 2) on the lower ends of uprights 5 and 6 45 so that slack may be taken up in the chains 31 as desired.

These chains 31 form part of a pile elevator which, as herein shown, is of the endless ladder type and includes spaced horizontal rails 35 50 having bevelled edges 37. The rails 36 are secured in any suitable manner on follower plates 38 pinned or otherwise suitably secured at equal intervals on the chains 31 and provided with rollers 39 and 40. Disposed at opposite sides of 55 the feeder and bolted or otherwise suitably secured to the uprights 5 and 6 are horizontally extending upper and lower bars 41 and 42 respectively which, in turn, have bolted or otherwise suitably secured thereto vertically extending 60 ing tracks 43 provided with vertical slots 44.

During operation of the elevator 31, 36, the following plates 38 pass through the slots 44 of tracks 43, and the rollers 39 and 40 travel on opposite sides of said tracks respectively. The 65 rails 36 on the inner opposed reaches of chains 31 are thus guided and maintained in proper laterally spaced relation for the loading, elevation, and reloading of piles A of sheets, as hereinafter described. Positioned within the feeder 70 at the bottom thereof, and projecting rearwardly therefrom, are stringers 45 having supports 46 which rest on the feeder foundation. These stringers 45 have bolted or otherwise suitably secured to the tops thereof channel members 47 75 having journalled therein at intervals therealong

rollers 48 on which piles of sheets A may be freely run into the feeder to load and reload the same.

Accordingly, the piles A of sheets are placed on skid boards 49 provided in the upper surfaces thereof with grooves 50 for a purpose hereinafter 5 described. These skid boards 49 have runners 51 and when the sheets 12 are placed in piles A on said skid boards the latter and the piles A of sheets thereon may be run by trucks to the feeder for loading thereon at intervals as required. For this purpose, pile boards 52 are employed having rail engaging plates 53 secured in any suitable manner on opposite side edges of said pile boards and depending below the bottoms thereof. When the feeder is to be initially 10 loaded with a pile A of sheets 12, a pile board is placed on the rollers 48 at the rearwardly projecting ends of stringers 45 (Fig. 1). The pile A and its supporting skid board 49 is then loaded by a truck on said pile board and the latter, the 15 skid board 52 and pile A of sheets thereon are rolled on rollers 48 into the feeder through the rear thereof to the position shown in dotted lines in Fig. 1 and full lines in Fig. 2, respectively, so that the opposite sides of the pile board 52 will 20 be disposed slightly above a pair of rails 36 of the pile elevator which, at this time, is stopped in order to receive the initial load.

In accordance with the present invention, each 25 load or pile A of sheets delivered on to the elevator is rapidly elevated thereby to proper position for feeding of the sheets 12 one after another from the top of the load or pile. As herein shown, this rapid elevation of the initial and subsequent piles A is preferably accomplished by mechanism constructed and operated as follows.

Extending across the feeder frame and secured in any suitable manner to the front uprights 5 30 thereof are cross shafts 54 (Figs. 1 and 3). Secured in any suitable manner in spaced relation on the cross shafts 54 are brackets 55 which have bolted or otherwise suitably secured thereto an electric motor 56 connected with a suitable source 35 of current and controlled for starting and stopping purposes by suitable switch means (not shown). Fixed on the armature shaft 57 of motor 56 is a sprocket 58 around which passes a chain 59 that also passes around a sprocket 60 40 that is fixed on the extension shaft 61 of a pump 62 suitably constructed to supply air under pressure from one side thereof and to create vacuum in another side thereof. This air and vacuum pump 62 is bolted or otherwise suitably secured 45 above the motor 56 on brackets 63 which, in turn, are secured in spaced relation in any suitable manner on the uppermost cross shaft 54 and a cross shaft 64 located thereabove and secured in 50 any suitable manner on the front uprights 5. Secured in any suitable manner in spaced relation 55 on the uppermost cross shaft 54 and the cross shaft 64 are brackets 65 (Fig. 1) which have bolted or otherwise suitably secured thereto in spaced relation plates 66 (Fig. 3) provided there- 60 in with bearing's for the extension shaft 61 of pump 62 and through which said shaft extends. Mounted in spaced relation on the shaft 61 between the plates 66 are clutches 67, 68 of well known construction and a clutch engaging and 65 releasing device 69 therebetween provided with 70 a grooved collar 70.

The clutch 67 has a part 71 fixed on shaft 61 and a part 72 loose on said shaft and provided with a spur pinion 73. The pinion 73 meshes 75 with a large gear 74 that is fixed on a shaft 75

journalled in suitable bearings in the plates 66. The clutch 68 has a part 71' fixed on the shaft 61 and a part 76 loose on said shaft and provided with a spur pinion 77. The spur pinion 77 meshes with a similar pinion 78 journalled in any suitable manner on one of the plates 66. This pinion 78, in turn, meshes with a small gear 79 that is fixed on the shaft 75. The shaft 75 projects outwardly through the outermost plate 66 and fixed on the projecting end of said shaft is a sprocket 80 around which passes a chain 81 that also passes around a sprocket 82 that is fixed on shaft 22 on an end thereof projecting outwardly through one of the brackets 23.

15 Bolted or otherwise suitably secured at one side of the feeder on the adjacent uprights 5 and 6 are brackets 83 (Fig. 1) in which is journalled a rock shaft 84 having fixed on the rear end thereof a handle 85. Fixed on the front end of 20 rock shaft 84 is an arm 86 having pivotally connected therewith the upper end of a rod 87 the lower end of which is pivotally connected with an arm 88 that is fixed on a short shaft 89 journalled on an arm 90 of a bracket 91 that is fixed 25 in any suitable manner between the plates 66 on a stay shaft 92 which connects said plates together (Figs. 3, 5 and 6).

The arm 88 is provided with a shoe 93 having downwardly and inwardly inclined faces 94, 95 terminating in a groove 96 normally receiving a 30 roller 97 journalled in any suitable manner on a plunger 98 projecting from a housing 99 secured to or formed integrally with bracket 91. The plunger 98 is provided therein with a recess 100 against the bottom of which bears one end of a spring 101 the opposite end of which bears 35 against a cover plate 102 secured in any suitable manner to the housing 99 at the top thereof.

The short shaft 89 also has fixed thereon a 40 downwardly extending arm 103 passing clear of a flattened portion 104 of a stay shaft 105 that also connects the plates 66 together. The lower end of the arm 103 is pivotally connected with one extremity of a link 106 the opposite extremity of which is pivotally connected with a 45 shift rod 107 slidably mounted in suitable openings in the plates 66 and extending therebetween. This shift rod 107 has fixed thereon a fork 108 the arms 109 of which are engaged in the groove 50 76 of the clutch engaging and releasing device 69.

In order to rapidly elevate the pile A of sheets that has been moved into the feeder as before described, the motor 58 is started by its switch 55 means and the armature shaft 61 of said motor then rotates clockwise as shown in Fig. 1. The handle 85, which has previously been held in the vertical neutral position thereof shown in Fig. 1 by the spring pressed plunger 98 and engagement of its roller 97 in the groove 96 of shoe 93, is pulled outwardly (Fig. 1) or toward the right (Fig. 3) and held in this position by the operator. This movement of handle 85 rocks shaft 84 and lowers rod 87 so that shoe 93 and the short shaft 89 are rocked counter-clockwise as viewed in Fig. 6 and the inclined face 94 of said shoe forces the spring pressed plunger 98 upwardly in housing 99. This rocking movement of short shaft 89 rocks arm 103 to the right (Fig. 6) and through the described connections for said arm with shift rod 107 the latter and fork 108 are also moved to the right (Fig. 6), thus actuating the device 69 (Fig. 3) so that the clutch 67 is thrown into operation.

75 The pinion 78 is thus connected with shaft 61

and through rotation of the latter by motor 58, gear 73 drives gear 74, shaft 75, chain 81, shaft 22, and chains 31 so that the inner reaches of the latter are rapidly raised and the lowermost pair of rails 36 are moved upwardly. The beveled 5 edges 37 of said pair of rails 36 engage plates 53 and the bottom of pile board 52 and through continued rapid elevation of said rails the pile board 52, and the skid board 49 and pile A of sheets thereon are lifted from the rollers 48 and 10 elevated until the top of said pile is at proper height for feeding of the sheets off the same one after another as hereinafter described.

When the top of the pile A is at proper height, the operator releases handle 85 which is then 15 moved inwardly (Fig. 1) or to the left (Fig. 3) by the spring pressed plunger 98 to its normal vertical and neutral position. The parts connected with handle 85 are thus also returned to their neutral positions by plunger 98. This 20 throws the clutch 67 out of operation and disconnects the drive for elevator 31, 36 from motor 58 through shaft 61 and gears 73, 74. During operation of the elevator to bring the initial load A up to feeding position the ratchet 25 will 25 rotate idly under pawl 24 without any interference therebetween. This enables the main feeder drive including the chain 13 to be operating while the feeder is being initially loaded, or reloaded as hereinafter described, without having to stop 30 said drive.

The feeder having been initially loaded, and the pile A of sheets moved upwardly to proper position as previously described, the inner reaches of chains 31 are then intermittently 35 moved upwardly step by step as sheets are fed one after another from the top of the pile by sheet separating and forwarding mechanism to be presently described. This intermittent elevation of the inner reaches of chains 31 and of the 40 pile A of sheets carried thereby is effected by the pawl and ratchet mechanism 24, 25 and is controlled by detector means hereinafter referred to. The means for separating and forwarding sheets one after the other from the top 45 of the properly elevated pile A comprises pile winding devices, sheet separating devices, sheet winding devices, sheet forwarding devices, and sheet conveying devices which will be described in the order named. 50

The pile winding devices (Figs. 1, 2 and 7) are comprised by vertically elongated nozzles 110 disposed at the rear of the pile and secured to or formed integrally with pipes 111 yieldably and adjustably mounted in any suitable manner on a 55 cross bar 112 disposed over the pile A at the rear thereof. This cross bar 112 is bolted or otherwise suitably secured to brackets 113 adjustably secured on side bars 114 which, together with said rear cross bar, form a frame the front end of 60 which is pivoted at 115 on brackets 116 bolted or otherwise suitably secured to the side frame members 7 and 8 near the fronts thereof. The rear end of the frame 112, 114 rests on pins 117 secured in any suitable manner to and projecting 65 inwardly from the rear uprights 6. The pile winding nozzles 110 together with other devices mounted on cross bar 112 are adjustable along the latter for different widths of sheets, and said bar and the nozzles and devices carried thereby 70 are adjustable along the side bars 114 for sheets of various lengths.

The pipes 111 of the pile winding nozzles 110 are connected by flexible conduits 118 with the ported casing 119 of a rotary valve mechanism 75

indicated broadly at 120 (Figs. 2 and 3). The cam shaft 18 extends loosely through the valve casing 119 and said casing is supported on a tubular shaft 121 extending transversely of the feeder and secured in any suitable manner to the front uprights 5. The rotary valve mechanism 120 is of the type shown in the application of Leonard Baker, George A. Martin and Leo C. Williams, Serial No. 116,692 filed December 19, 10 1936. It controls the delivery of air to the pile and sheet winding devices and the making and breaking of vacuum in the sheet separating and forwarding devices as described in said application Serial No. 116,692 and includes a rotary air valve 122 and a rotary vacuum valve 123 fixed on cam shaft 18 at opposite sides of the casing 119 and having ports cooperating with ports in said casing, and discs 124 and 125 fixed on said cam shaft at the outer sides of said valves. 15

20 The tubular shaft 121 has two divided parts 126, 127 the part 126 being connected by a flexible conduit 128 with a tank 129 secured, as by a strap 130, to the front face of the plate or apron 11. This tank 129 is supplied with air 25 under pressure from the air side of pump 62 by a conduit 132 connected with said side of the pump and said tank. It will thus appear that through the described connections between the air side of pump 62 and pipes 111, and by control of the 30 air valve 122 of the mechanism 120, air under pressure will be supplied through nozzles 110 to wind the uppermost sheets of pile A at proper intervals.

35 The sheet separating devices are preferably of the type disclosed in application Serial No. 116,692 above referred to and include suction cups 133 fixed on the lower ends of tubular pistons 134 having reciprocating working strokes of considerable length in cylinders 135 supported by brackets 136 mounted on the cross bar 112 for adjustment therealong to any desired position. (Figs. 1, 2 and 7.)

40 The suction cups 133 and pistons 134 are, as in application Serial No. 116,692 above referred to, 45 spring operated in one direction and vacuum operated in the other direction and for this purpose springs (not shown) are disposed in cylinders 135 between the pistons 134 and the upper cylinder heads and the cylinders are connected 50 with the vacuum side of pump 62. Accordingly, cylinders 135 have connected therewith flexible conduits 137 which are also connected with suitable ports in valve casing 119 controlled by valve 123. These ports are further connected with the 55 part 121 of tubular shaft 121 which part, in turn, is connected with a flexible conduit 138. The conduit 138 is connected with an L-shaped conduit 139 that is also connected with the vacuum side of pump 62 which side is connected by 60 a conduit 131 with the air side of said pump for delivery of exhaust air therein. It will thus appear that through the described connections for cylinders 135 with the vacuum side of pump 62, and by control of the vacuum valve 123 of mechanism 120, vacuum will be created in said cylinders 65 at proper intervals and, with the springs therein, will reciprocate the pistons 134 and cups 133, with strokes of considerable length, to engage said cups with the sheets of pile A and initially 70 separate said sheets therefrom in proper sequence.

75 As each sheet is initially separated or lifted from the top of the pile by pistons 134 and cups 133, a blast or blasts of air are directed between the pile and the separated sheet to completely separate it from said pile in the direction in which

the sheet is carried forward therefrom. This is accomplished by directing air under pressure at proper intervals through nozzles 140 located adjacent the top and rear of the pile and secured to or formed integrally with pipes 141. The pipes 141 and nozzles 140 are adjustably mounted in any suitable manner on the cross bar 112 and may be adjusted, as desired, both laterally and vertically with respect to said bar in accordance with the width of the sheets and the height of 10 the top of the pile A. The pipes 141 have connected therewith flexible conduits 142 which are also connected with suitable ports in the valve casing 119 through which air under pressure is delivered from the part 126 of tubular shaft 121. 15 It will thus appear that through the described connections for nozzles 140 with the source of air under pressure, and by control of the air valve 122 of mechanism 120, air under pressure will be delivered through said nozzles at proper 20 intervals to wind each sheet separated or lifted from the pile by the above described sheet separating devices.

25 The sheets separated one after another from the top of pile A are forwarded in like manner relative thereto by sheet forwarding devices of the type illustrated and described in application Serial No. 116,692 above referred to. These sheet forwarding devices include vacuum cups 143 fixed on the lower ends of tubular pistons 144 having 30 working strokes of considerable length in cylinders 145. These cylinders 145 are bolted or otherwise suitably secured to arms 146 fixed on a rock shaft 147 extending transversely of the feeder and journalled in suitable bearings in the brackets 35 116 at the top and front of the feeder (Figs. 1, 3 and 7). The vacuum cups 143 and the tubular pistons 144, as in application Serial No. 116,692, are spring operated in one direction and vacuum operated in the opposite direction. For this purpose springs (not shown) are disposed in the cylinders 145 between the pistons 144 and the upper heads of the cylinders, and said cylinders are connected with the vacuum side of pump 62 as follows. The cylinders 145 have connected therewith flexible conduits 148 which are also connected with suitable ports in the casing 119 of valve mechanism 120. These last named ports are also connected through casing 119 with the vacuum part 127 of tubular shaft 121 and are 40 controlled by the vacuum valve 123 of said valve mechanism. It will thus appear that through the described connections for cylinders 145 with the source of vacuum, and by control of the vacuum valve 123, vacuum will be intermittently created and broken in said cylinders and with the springs therein, will reciprocate the pistons 144 and vacuum cups 143 so that the latter engage and further lift the separated sheets at proper 45 intervals and release said sheets when the same 50 are forwarded by swinging motion of said pistons and cylinders.

55 Swinging motion of cylinders 145 and the sheet forwarding devices is effected by a cam 149 and a spring 150 (Fig. 7). The cam 149 is fixed on 60 cam shaft 18 and engages a roller 151 journalled on a fork 152 between which the cam shaft extends. This fork 152 is secured to or formed integrally with a strap 153 which is pivotally connected with an arm 154 that is fixed on the rock 65 shaft 147. The spring 150 has one end connected with the arm 154 and the opposite end secured on a pin 155 on side member 8. Spring 150 holds roller 151 engaged with cam 149 so that through 70 rotation of said cam and the action of said spring 75

the cylinders 145 and sheet forwarding devices therein are oscillated to engage, forward and release the separated sheets in succession.

The separated and forwarded sheets are delivered by the forwarding devices to a conveyor which carries the sheets to the machine being fed therewith. As herein shown this conveyor includes a shaft 156 (Figs. 1, 3 and 7) extending transversely of the feeder and journaled in suitable bearings in the front uprights 5. This shaft 156 is driven from the short shaft 15 which, for this purpose, has fixed thereon a large gear 157 which meshes with a similar gear 158 that is fixed on the shaft 156. The shaft 156 has fixed thereon in spaced relation outer feed rollers 159 and inner feed rollers 160 around which pass tapes 161 that also pass around a front conveyor roller (not shown). Cooperating with a pair of the feed rollers 160 and the adjacent tapes 161 for delivery of the separated and forwarded sheets thereby, are drop rollers 162 journaled on arms 163 that are fixed on a rock shaft 164 extending transversely of the feeder and journaled in suitable bearings in side plates 165 bolted or otherwise suitably secured to the front uprights 5 and extending forwardly thereof.

The rock shaft 164 has fixed thereon an arm 166 provided with a roller 167 that is engaged intermittently by a cam 168 secured to or formed integrally with the disc 124 that is fixed on and rotated by cam shaft 18. The drop rollers 162 are lowered at intervals by a spring (not shown) and are raised at intervals by cam 168 in timed relation with the action of the sheet forwarding devices so that when said drop rollers are lifted a sheet is forwarded by said devices between the drop rollers and the feed rollers 159, 160 whereupon the drop rollers are lowered to advance the sheet and the forwarding devices recede to engage the next sheet. These operations are repeated to facilitate forwarding and conveying of the sheets one after another in proper sequence.

As the sheets are separated and forwarded one after another from the top of the pile in the manner described above, the inner reaches of chains 131 are intermittently raised to elevate the pile of sheets. This intermittent raising of the pile is preferably controlled by mechanism constructed and operated as follows. A detector 169 in the form of a ball rests continuously by gravity on the top of the pile and is freely mounted in the lower end of a gravity plunger 170 that is slidably mounted in a housing 171 adjustably secured in any suitable manner on the cross bar 112. This housing 171 has connected therewith one end of a flexible conduit 172 the opposite end of which is connected with a housing 173 having a spring pressed plunger 174 extending downwardly therethrough and adapted, under certain conditions, to engage a pawl mask 175 loosely mounted on shaft 22 adjacent the ratchet 25 and yieldably connected with the pawl carrier 21.

The construction and operation of the pile detector 169 and the mask engaging plunger 174 is the same as the construction and operation of the pile detector and mask engaging plunger illustrated and described in application Serial No. 116,692 above referred to and needs no detailed description herein. It is sufficient to say that when a quantity of sheets have been fed off the top of the pile, the detector 169 through lowering action thereof by gravity, causes operation of the elevator 31, 36 to raise the pile. For

this purpose, the part 128 of tubular shaft 121 has connected therewith one end of a flexible conduit 176 the opposite end of which is connected with the housing 171 so that air under pressure is supplied therein.

Upon abnormal lowering of the detector 169, as above described, this air under pressure is delivered from housing 171 through conduit 172 into housing 173. The air under pressure thus delivered into housing 173 forces the plunger 174 downwardly against the action of its spring into engagement with the pawl mask 175. This mask 175 is rotated by pawl carrier 21 when the elevator is at rest but when the plunger engages the mask rotation of the same is stopped and the pawl 24 is thereupon permitted to engage the ratchet 25 which, through oscillation of said pawl, is rotated and thereby rotates shaft 22 to raise the elevator and the pile of sheets thereon. When the top of the pile reaches a certain height, the detector 169, having been lifted by the pile while still maintained in engagement therewith, shuts off the supply of compressed air through conduit 172 to plunger housing 173 and the spring therein for its plunger 174 raises the latter out of engagement with the mask 175 so that said mask is permitted to rotate, hold the pawl 24 out of engagement with the ratchet 25, and thus prevent further elevation of the pile until this is again necessary. These operations are repeated at intervals as the sheets are fed continuously from the top of said pile.

In accordance with the present invention, means are provided enabling the feeder to feed sheets continuously from the top of a continuous supply and this supply is continuously maintained by new loads or piles of sheets placed at intervals in the feeder and each run up vertically under a preceding load or supply to replenish the same. This continuous feeding of sheets from the supply and replenishing thereof is preferably accomplished as follows.

Assuming that original pile A of sheets has been lifted step by step by the described means for this purpose as sheets have been fed off the top of said pile successively by the sheet separating and forwarding devices, the top of the skid board 49 will arrive at a certain position thereof in which position of said board a temporary removable support in the form of a fork 177 is placed in the feeder to support the remainder of the pile A of sheets.

This fork is placed in the feeder through the rear thereof, the tangs 178 of the fork being inserted in the grooves 50 of the skid board 49 under the remainder of the pile of sheets thereon. When the tangs 178 are so inserted in grooves 50, the free ends of said tangs pass through notches 179 formed on the top of the apron or plate 11 and rest thereon, and the head 180 of said fork rests on pins 181 secured in any suitable manner on brackets 182 that are bolted or otherwise suitably fastened on the rear uprights 6 and project inwardly therefrom as clearly shown in Fig. 4. In this position of fork 177 (Fig. 7) it is located at a distance from the sheet separating and forwarding devices substantially equal to the length of their maximum working strokes so that said devices can feed the sheets of the remainder of the pile supported on the fork one after another without elevation of said remainder of the pile.

The remainder of the pile A of sheets now being supported on the fork 177, the sheet separating and forwarding devices which, as pointed

out, have working strokes of considerable length, continue to operate and feed sheets one after another from the top of the remainder of the pile supported on said fork. The elevator is now 5 operated so that the inner reaches of chains 31 are lowered sufficiently to bring the pair of rails 36 that have been carrying the original pile board 52 and skid board 49 into alinement with tracks 183 on which said pile and skid boards 10 may be run outwardly through the rear of the feeder and removed therefrom as shown in Fig. 1. The front ends of tracks 183 are bolted or otherwise suitably secured on the rear uprights 6 and spaced inwardly therefrom in any suitable manner, and the rear ends of said tracks are bolted or otherwise suitably secured to, and spaced from, the lower ends of inclined bars 184. The upper 15 front ends of the inclined bars 184 are bolted or otherwise suitably secured to the rear uprights 6.

Lowering of the inner reaches of the elevator chains 31 to remove the empty pile and skid boards is accomplished as follows. The handle 85 is pushed inwardly (Fig. 1) or to the left (Fig. 3) 25 and held in this position by the operator so that the pawl and ratchet mechanism 24, 25 is thrown out of operation and the clutch 68 is thrown into operation. For throwing the pawl and ratchet mechanism 24, 25 out of operation, the rock shaft 30 84 has fixed thereon near its forward end an arm 185 having a pin and slot connection 186, 187 with a small link 188 that is pinned or otherwise suitably secured to a shift rod 189. This 35 shift rod 189 extends transversely of the feeder and is slidably mounted in suitable openings in brackets 23. Fixed on shift rod 189 is a fork 190 the arms 191 of which engage in a groove 192 formed in the pawl mask 175. When the 40 lever 85 is shifted to the left (Fig. 3) the shift rod 189, the fork 190, and the mask 175 are moved to the right so that said mask lifts the pawl 24 and holds it out of engagement with the ratchet 25.

Upon shifting of the lever 85 to the left (Fig. 3) 45 or inwardly (Fig. 1), the rod 87 is raised, thus rocking the arm 88 and moving the arm 103 to the left (Fig. 6). The face 95 of shoe 93 thus moves to the right and forces plunger 98 upward from its normal position in the groove 96 of said shoe. Movement of arm 103 to the left (Fig. 6) causes corresponding movement of link 106, shift rod 107, and fork 108, thus throwing clutch 68 into operation so that gears 71, 78, 79, chain 81 and shaft 22 are driven in the proper direction 50 to lower the inner reaches of chains 31 of the elevator and bring the pair of rails 36 supporting the empty pile and skid boards into alinement with tracks 183 for removal of said boards as before described. When said pair of rails 36 is 55 brought into alinement with tracks 183, the elevator is stopped by releasing handle 85 which is then moved by spring pressed plunger 98 to its vertical or neutral position thus throwing the clutch 68 out of operation and disconnecting the drive for elevator 31, 36 from motor 56 through shaft 61 and gears 71, 78 and 79. Under these 60 conditions shift rod 189 is moved to the left (Fig. 3) by a spring 194 mounted on said rod between a collar 195 thereon and one of the 65 brackets 23. This movement of rod 189 is limited by a second collar 196 thereon and when rod 189 is moved as aforesaid, the mask 175 is moved thereby back to its operative position. While sheets are being separated and fed from the top 70 of the remainder of the original pile on fork

177, and after the original pile board and skid board are removed from the feeder, a second pile board which has been placed on the rollers 48 at the rearwardly projecting ends of stringers 45 and loaded with a second skid board and pile A 5 of sheets is run therewith into the feeder, as in the case of the first pile or load, to position for elevation by the elevator to normal feeding position.

The handle 85 is then again moved outwardly 10 (Fig. 1) or to the right (Fig. 3) and held in this position by the operator, thus throwing clutch 67 into operation. The gears 73, 74, the chain 81, and the shaft 22 are thus driven from motor 56 15 so that chains 31 of the elevator are operated to bring a pair of rails 36 around sprockets 32 and upwardly under the new pile board into engagement with plates 53 thereof and the bottom of said board. Continued upward movement of the last mentioned pair of rails 36 lifts the new pile 20 board 52 and the new skid board and load of sheets thereon upwardly until the top of the new pile is brought up into contact with the fork 177. In the meantime the ratchet 25 rides idly past the oscillating pawl 24 so that the latter has no 25 effect on said ratchet and the elevator.

The lever 85 is now released and moved by plunger 98 to normal or vertical position thus throwing clutch 67 out of operation and stopping the drive of shaft 22 through chain 81. The 30 fork 177 is then removed from the feeder through the rear thereof as shown in dotted lines in Fig. 7, and any remaining sheets of the previous pile are prevented from being displaced rearwardly with the fork by guides 193 adjustably mounted in any 35 suitable manner on the cross bar 112. The remaining sheets of the previous pile now rests on top of the new pile and separation and forwarding of the sheets from the top of said pile and step by step elevation thereof continue through 40 the medium of the described devices for this purpose.

It will appear from the foregoing, that the feeder having been set into operation, feeding of sheets therefrom may proceed continuously without interruption, by temporarily supporting the remainder of each pile of sheets, reloading a new pile thereunder, withdrawing the supporting fork, and elevating the pile step by step, as described, and repeating these operations as necessary or required. 50

Having now described my invention what I claim is:

1. In a sheet feeder, a pile elevator, means for intermittently operating the pile elevator, other means for operating said pile elevator, manually insertable sheet supporting means manually removed from sheet supporting position when the pile elevator is operated by its first named operating means and movable into sheet supporting position when said elevator is operated by its second named operating means, means having a neutral inoperative position and movable in opposite directions therefrom for selectively throwing said two elevator operating means into and out of operation, and means for automatically returning said last named means to its neutral inoperative position after movement of the same as aforesaid in either of said directions. 60

2. In a sheet feeder, mechanism for elevating a pile board and a pile of sheets thereon until the board reaches a certain height, manually insertable means moved at said height to sheet supporting position between the board and pile for supporting a remainder of the latter, said 65 70 75

means being manually removed from sheet supporting position after a second pile board and pile of sheets thereon have been loaded on the elevating mechanism and raised thereby to bring 5 the top of the second pile to the level of the bottom of the remainder of the elevated first pile, means on the feeder onto which empty pile boards may be transferred from the elevating mechanism, and means for operating said elevating 10 mechanism for the purposes aforesaid.

3. In a sheet feeder, means at the bottom thereof for running pile boards and piles of sheets thereon into the feeder, an elevator for lifting a board and pile from said means and for continuing the elevation thereof until the board reaches a certain height, manually insertable 15 supporting means moved at said height to sheet supporting position between the board and pile for supporting a remainder of the latter, said 20 supporting means being manually removed from sheet supporting position when the elevator has been operated for removal of the board therefrom and to lift a second board and pile thereon from said first named means and raise the second board and pile until the top of the latter reaches the level of the bottom of the remainder 25 of the elevated first pile, means on the feeder onto which empty pile boards may be transferred from the elevator, and means for operating 30 said elevator for the purposes aforesaid.

4. In a sheet feeder, a frame, tracks on the frame, an elevator on said frame comprising endless chains and horizontal pile board engaging rails movable into alignment with the tracks for 35 transfer of empty pile boards from the rails to the tracks, and means for operating the elevator to bring the rails thereof into alignment with said tracks for the purposes aforesaid.

5. In a sheet feeder, a frame, means at the bottom 40 of the frame for running pile boards and piles of sheets thereon into the frame, an elevator on the frame comprising endless chains and horizontal rails for lifting boards and piles of sheets thereon from said means and continuing the elevation of each board and pile for feeding of sheets 45 therefrom, and tracks on the frame with which the rails may be aligned by said chains to transfer empty pile boards from said rails to said tracks.

6. In a sheet feeder, a frame, means at the bottom 50 of the frame for running pile boards and piles of sheets thereon into the frame, rail engaging means on opposite sides of each pile board, and an elevator on the frame comprising endless chains and horizontal beveled edged rails for engaging 55 said rail engaging means and boards and lifting the latter and piles of sheets thereon from said first named means.

7. In a sheet feeder; a frame; vertical tracks on the frame and provided with vertical slots; an 60 elevator on the frame comprising endless chains, follower plates on the chains traveling through the slots of the vertical tracks, rollers on the follower plates traveling on opposite sides of said tracks, and horizontal pile and pile board lifting 65 and elevating rails secured to said follower plates; and means for operating said elevator.

8. In a sheet feeder, flexible means for supporting, feeding and replenishing a supply of sheets, power actuated mechanisms for selectively 70 operating the flexible means intermittently to feed the supply or continuously and rapidly to feed other sheets and replenish the supply therewith, means normally removed from the feeder and manually movable therein at a predetermined position in the path of travel of the supply to sup-

port and hold said supply stationary while it is being replenished, means located on the feeder in said position for supporting the manually movable means and the supply in said feeder, and means for selectively throwing said power actuated mechanisms and said flexible means into intermittent or continuous and rapid operation.

9. In a sheet feeder, vertically extending flexible pile supporting, elevating and replenishing means adjacent opposite sides of the feeder, power 10 actuated mechanisms for selectively operating the flexible means intermittently to feed an elevated pile of sheets or continuously and rapidly to replenish the elevated pile by elevating another pile thereto under the same, auxiliary means normally removed from the feeder and manually movable therein through the rear thereof at a predetermined elevation in the upward path of travel of the first pile to support and hold said first pile stationary while the second pile is elevated thereto as aforesaid, means on the front and rear of the feeder at said elevation for supporting said auxiliary means and the supply in said feeder, and means for selectively throwing said power actuated mechanisms and said flexible 15 means into intermittent or continuous and rapid operation.

10. In a sheet feeder, vertically extending flexible means at opposite sides of the feeder for supporting, elevating and replenishing piles of sheets, 20 motor actuated mechanism for imparting continuous and rapid movement to the flexible means whereby it may rapidly raise a pile loaded thereon at the bottom of the feeder to feeding position under and in contact with the bottom of a preceding 25 elevated pile diminished through feeding of sheets from the top therof, means normally removed from the feeder and manually movable therein at a predetermined elevation under the elevated and diminished pile to support it while 30 the succeeding pile is elevated thereto under the same by the flexible means, power actuated mechanism for imparting intermittent elevating movement to the flexible means and each pile raised to said feeding position whereby the top of the 35 pile is maintained at a predetermined level as sheets are fed therefrom, and means for selectively throwing said motor and power actuated mechanisms into and out of operation.

11. In a sheet feeder, vertically extending flexible means at opposite sides of the feeder for supporting, elevating and replenishing piles of sheets, 40 motor actuated mechanism for imparting continuous movement to the flexible means whereby it may rapidly raise a pile loaded thereon at the bottom of the feeder to feeding position under and in contact with the bottom of a preceding elevated pile diminished through feeding of sheets from the top thereof, manually displaceable means normally removed from the feeder and 45 manually positioned therein at a predetermined elevation under the elevated and diminished pile for supporting it stationary while the succeeding pile is elevated thereto under the same by the flexible means, supports on the feeder at said elevation for receiving and holding said manually displaceable means in pile supporting position, power actuated mechanism for imparting intermittent elevating movement to the flexible means and each pile raised to said feeding position 50 whereby the top of the pile is maintained at a predetermined level as sheets are fed therefrom, and means for selectively throwing said motor and power actuated mechanisms into and out of operation.

12. In a sheet feeder, flexible means for feeding a supply of sheets and for adding sheets to the bottom of the supply when it is diminished through removal of sheets from the top thereof, 5 power driven means for operating the flexible means intermittently as sheets are removed from the supply and for operating the flexible means continuously and rapidly when it adds sheets to said supply, means manually movable into and 10 out of a supply supporting position on the feeder for supporting the supply stationary when it is diminished and while sheets are being added to the bottom of the supply by said flexible means, and means for selectively throwing said power driven means and said flexible means into intermittent or continuous and rapid operation.
13. In a sheet feeder, vertically disposed flexible means for elevating a supply of sheets and for adding sheets vertically to the bottom of the 20 supply when it is diminished through removal of sheets from the top thereof, power driven means for operating the flexible means intermittently and upwardly as sheets are removed from the supply and for operating the flexible 25 means continuously and rapidly when sheets are added vertically to the bottom of the supply, means manually movable horizontally into and out of a supply supporting position on the feeder for supporting the supply stationary when it is diminished and while sheets are being added vertically to the bottom thereof by said vertically 30 disposed flexible means, and means for selectively throwing said power driven means and said flexible means into intermittent or continuous 35 and rapid operation.
14. In a sheet feeder, vertically disposed flexible pile feeding mechanism provided at intervals therealong with a plurality of means for supporting sheet piles, said mechanism and one of said 40 means being adapted to elevate a pile and support the same until it is diminished by feeding of sheets from the top thereof and said mechanism and another of said means being adapted to support and elevate a new pile to the bottom of 45 the preceding diminished pile, power driven means for operating the flexible mechanism intermittently and upwardly as sheets are removed from the top of a pile and for operating the flexible mechanism continuously and rapidly to elevate 50 and add the new pile to the bottom of the preceding diminished pile, means manually movable into and out of a pile supporting position on the feeder for supporting the diminished pile 55 stationary while the new pile is elevated to the bottom thereof by said mechanism, and means for selectively throwing said power driven means and said flexible mechanism into intermittent or continuous and rapid operation.
15. In a sheet feeder, pile elevating and feeding mechanism comprising vertically disposed 60 flexible endless means at opposite sides of the feeder provided at corresponding intervals therealong with pairs of devices for supporting sheet piles, said means and one pair of devices thereon being adapted to elevate a sheet pile and support the same until it is diminished by feeding of sheets from the top thereof and said means and another pair of said devices being adapted 65 to support and elevate a new sheet pile to the bottom of the elevated diminished pile, power driven means for operating the flexible endless means upwardly and intermittently to feed the elevated pile and for operating the flexible endless means continuously and rapidly to elevate 70 the succeeding pile to the bottom of an elevated 75

diminished pile, means manually movable into and out of a pile supporting position on the feeder for supporting the diminished pile stationary while the new pile is elevated to the bottom thereof by said mechanism, and means for selectively throwing said power driven means and said flexible means into intermittent or continuous and rapid operation.

16. In a sheet feeder, pile elevating and feeding mechanism comprising vertically disposed 10 endless chains at opposite sides of the feeder provided at corresponding intervals therealong with pairs of horizontal rails for supporting sheet piles, said chains and one pair of rails thereon being adapted to elevate a sheet pile and support the same until it is diminished by feeding of sheets from the top thereof and said chains and another pair of said rails being adapted to support and elevate a new sheet pile to the bottom of the elevated diminished pile, power driven 15 means for operating the chains upwardly and intermittently to feed an elevated pile and for operating the chains continuously and rapidly to elevate the succeeding pile to the bottom of the preceding diminished pile, a temporary support comprising spaced elements manually movable into and out of pile supporting position on the feeder for supporting the diminished pile stationary while the succeeding pile is elevated to the bottom thereof by said mechanism, means on the feeder for supporting said temporary support therein and enabling it to be moved into and out of the feeder as desired, and means for selectively throwing said power driven means and said endless chains into intermittent or continuous 20 and rapid operation.

17. In a sheet feeder, flexible means for supporting, feeding and replenishing a supply of sheets, power driven means for selectively operating the flexible means intermittently to feed the supply or continuously and rapidly to feed other sheets and replenish the supply therewith, manually insertable means for supporting said supply stationary while it is being replenished, said manually insertable means being manually 45 removed from supply supporting position when the supply has been replenished, means on the feeder for supporting the manually insertable means in supply supporting position to hold the supply stationary while it is being replenished, and means for selectively throwing said power driven means and said flexible means into intermittent or continuous and rapid operation.

18. In a sheet feeder, flexible means for elevating a pile of sheets and for adding sheets to the bottom of the pile when it is diminished through removal of sheets from the top thereof, power driven means for operating the flexible means intermittently as sheets are removed from the top of the pile and for operating the flexible means continuously and rapidly when it adds sheets to the bottom of said pile, manually insertable means movable to pile supporting position for supporting the pile stationary while sheets are being added to the bottom thereof, said manually insertable means being manually removed from the pile supporting position when sheets have been added to the bottom of the pile, means on the feeder for supporting the manually insertable means in pile supporting position to hold the pile stationary while sheets are being added to the bottom thereof, and means for selectively throwing said power driven means and said flexible means into intermittent or continuous and rapid operation.

19. In a sheet feeder, flexible means for feeding a supply of sheets and for adding sheets to the bottom of the supply when it is diminished through removal of sheets from the top thereof, power driven mechanism for operating the flexible means intermittently as sheets are removed from the top of the supply and for operating the flexible means continuously when it adds sheets to the bottom of said supply, manually insertable means movable to supply supporting position for supporting the supply stationary while sheets are being added to the bottom thereof, said manually insertable means being manually removed from supply supporting position when sheets have been added to the bottom of the supply, means on the feeder for supporting the manually insertable means in supply supporting position to hold the supply stationary while sheets are being added to the bottom thereof, and means for selectively throwing said power driven mechanism into intermittent or continuous operation.

20. In a sheet feeder of the class having a pile elevator, mechanism for operating the elevator in opposite directions, and vacuum type sheet feeding means, the combination of supporting means adapted to hold an elevated and diminished pile of sheets within the range of action of the sheet feeding means while the elevator and its operating mechanism are employed to lift a new pile of sheets to the bottom of said elevated and diminished pile, a pump connected with the sheet feeding means for producing vacuum therein, and means for driving both the pump and the elevator operating mechanism without interrupting the vacuum producing operation of said pump, whereby said sheet feeding means feeds sheets without interruption from said elevated and diminished pile while said elevator and its operating mechanism are employed to lift said new pile of sheets as aforesaid.

21. In a sheet feeder of the class having a pile elevator, mechanism for operating the pile elevator in opposite directions, and vacuum type sheet feeding means, the combination of supporting means adapted to hold an elevated and diminished pile of sheets within the range of action of the sheet feeding means while the elevator and its operating mechanism are employed to lift a new pile of sheets to the bottom of said elevated and diminished pile, a pump connected with the sheet feeding means for producing vacuum therein, means operated in one direction only for driving both the elevator operating mechanism and the pump and operatively connected with the latter, and means for connecting the elevator operating mechanism with the driving means without disconnecting the pump therefrom and without interrupting its vacuum producing operation, whereby said sheet feeding means feeds sheets without interruption from said elevated and diminished pile while said elevator and its operating mechanism are employed to lift said new pile of sheets as aforesaid.

22. In a sheet feeder of the class having a pile elevator, mechanism for operating the elevator in opposite directions, and variable reach vacuum type sheet feeding means, the combination of removable means for supporting an elevated

and diminished pile of sheets stationary and within the range of action of the sheet feeding means while the elevator and its operating mechanism are employed to lift a new pile of sheets to the bottom of said elevated and diminished pile, a pump connected with the sheet feeding means for producing vacuum therein, and means for driving both the pump and the elevator operating mechanism without interrupting the vacuum producing operation of said pump, whereby said variable reach sheet feeding means feeds sheets without interruption from the stationary lifted and diminished pile on said supporting means while said elevator and its operating mechanism are employed to lift said new pile of sheets as aforesaid.

23. In a sheet feeder of the class having a pile elevator, mechanisms for selectively operating the elevator in opposite directions, and variable reach vacuum type sheet feeding means, the combination of removable supporting means adapted to hold an elevated and diminished pile of sheets stationary and within the range of action of the variable reach sheet feeding means while the elevator and its operating mechanisms are employed to lift a new pile of sheets to the bottom of said elevated and diminished pile, a pump connected with the sheet feeding means for producing vacuum therein, means for driving both the elevator operating mechanisms and the pump and operatively connected with the latter, and means for selectively connecting the elevator operating mechanisms with the driving means without interrupting the vacuum producing operation of the pump by the same, whereby said sheet feeding means feeds sheets without interruption from the stationary elevated and diminished pile on said supporting means while said elevator and its operating mechanisms are employed to lift said new pile of sheets as aforesaid.

24. In a sheet feeder of the class having a pile elevator, gear mechanisms for operating the elevator in opposite directions, and variable reach vacuum type sheet feeding means, the combination of removable supporting means adapted to hold an elevated and diminished pile of sheets stationary and within the range of action of the variable reach sheet feeding means while the elevator and the gear mechanisms are employed to lift a new pile of sheets to the bottom of said stationary elevated and diminished pile, a pump connected with the sheet feeding means for producing vacuum therein, a motor operated in one direction only for driving both the gear mechanisms and the pump and operatively connected with the latter, and clutch means for selectively connecting the gear mechanisms with the motor without disconnection of the pump therefrom and without interrupting its vacuum producing operation, whereby said sheet feeding means feeds sheets successively without interruption from the stationary elevated and diminished pile on said supporting means while said elevator and said gear mechanisms are employed to lift said new pile of sheets to the bottom of said stationary elevated and diminished pile.

LEONARD BAKER.
